Patented Mar. 23, 1971

220,301

COMB

Gino J. Piermarini, 443 Pleasant St., and Norman C.
Burnap, 319 Pierce St., both of Leominster, Mass.
01453

Filed Oct. 9, 1969, Ser. No. 19,481

Term of patent 14 years

Int. Cl. D28—03

U.S. Cl. D86—8

Fig. 1

Fig. 2

Fig. 3

FIG. 1 is a side elevational view of a comb showing our new design, the side opposite being a mirror image thereof;

FIG. 2 is a top plan view thereof; and

FIG. 3 is an end elevational view as seen from the left of FIG. 1.

We claim:

The ornamental design for a comb, as shown and described.
